Primary Examiner — Karen S Acker*Assistant Examiner* — Wendy Arminio(74) *Attorney, Agent, or Firm* — Eugene J. A. Gierczak(57) **CLAIM**

The ornamental design for a closure vent with body skirt and hinged cap, as shown and described.

DESCRIPTION

FIG. 1 is a perspective view of a closure vent with body skirt and hinged cap with the resealable cap shown in an open position.

FIG. 2 is a side view thereof.

FIG. 3 is a partial cross-sectional side view of the design of FIG. 1 taken along line 3-3 of FIG. 5 showing the resealable cap in an open position and the frangible vent located near the body center axis in a closed position.

FIG. 4 is a partial cross-sectional side view of the design of FIG. 1 taken along line 4-4 of FIG. 5 showing the resealable cap in a partially closed position and the frangible vent located near the body center axis in an open position.

FIG. 5 is a top view of the closure vent with body skirt and hinged cap of FIG. 1; and,

FIG. 6 is a bottom view thereof.

The design consists of the features of shape, pattern and configuration of a vent closure for plastic pails consisting of a cylindrical body with skill, frangible vent near the body center axis and a resealable cap attached to the body with a flexible hinge.
